UNITED STATES PATENT OFFICE.

JOHN B. HASTY, OF SAN BERNARDINO, CALIFORNIA, ASSIGNOR TO LOVEJOY TOOL WORKS, OF CHICAGO, ILLINOIS, A CORPORATION OF ILLINOIS.

JACK.

1,427,459.

Specification of Letters Patent. Patented Aug. 29, 1922.

Application filed October 2, 1918. Serial No. 256,585.

To all whom it may concern:

Be it known that I, JOHN B. HASTY, a citizen of the United States, residing in San Bernardino, in the county of San Bernardino 5 and State of California, have invented a new and useful Improvement in Jacks, of which the following is a specification.

This invention relates in general to jacks and has for its object broadly the provision 10 of means for preventing forcing the jack beyond a predetermined lifting action well within the capacity of the jack.

A principal object of the invention is the provision of means in a jack for controlling 15 the action so that it will be impossible to give to the jack more than a predetermined lifting movement, to the end that effort may not be made by exerting too great strain upon the parts to operate the jack beyond its lifting 20 movement with resultant damage to the working parts.

The invention contemplates the provision of means for accomplishing this purpose, which will not interfere in any way with the 25 normal and usual manner or method of operating a jack in which my invention may be employed, and without greatly increasing the cost of the article or material contained in its construction.

30 The invention contemplates an automatic interruption of the chain of power transmitting mechanisms beginning at the handle at the power receiving end and ending at the lifting head when the desired limit of elevation is reached, and contemplates the immediate operative restoration of the continuity of the chain when the handle is manipulated to lower the jack.

Numerous other objects and advantages of 40 the invention will be apparent as it is better understood from the following description when considered in connection with the accompanying drawing illustrating a preferred embodiment thereof.

45 On the drawings,

Figure 1 is a section taken vertically of a jack embodying my invention;

Fig. 2 is a horizontal section taken substantially upon the axis of the prime actuator;

Fig. 3 is a side elevation of the manipulating member and casing;

Fig. 4 is a transverse section therethrough showing the arrangement of the parts during the elevation of the jack;

Fig. 5 is a partial view similar to Fig. 2, showing the arrangement of the parts at the end of the lifting action;

Fig. 6 is a section taken on the line 6—6 of Fig. 5; 60

Fig. 7 is a perspective view of the ratchet pawl;

Fig. 8 is an end elevation of the ratchet wheel; and

Fig. 9 is a similar view of the spring 65 provided to return the parts to normal position after each actuation.

The jack shown on the drawing for the purpose of illustrating my invention, consists of a casing 11 in which is mounted the vertical lifting screw 12 engaging the threaded lift member 13 bearing a lift head 10. The lifting screw 12 is fixed to a bevel gear 14 having bearing upon the bottom of the casing. A prime actuator, comprising a 70 shaft 15 and a driving bevel gear 16 meshing with the gear 14, is provided and is mounted in a bearing bracket or plate 17 secured by screws 18 to the casing 11 and covering an opening 19 in its side wall. The 75 bearings for the shaft 15 comprises a fixed bearing 21 and a sliding bearing 22 movable in a bore 23 provided in a neck or extension 24 of the plate 17, a key or spline 25 being provided to prevent rotation of the sliding bearing 22 for a purpose to be later described. 85

A manipulating device for actuating the prime actuator comprises a casting 26 embracing the shaft 15 and having a lever or handle receiving socket 27 and a driving pawl receiving socket 28. The portion 29 of the shaft 15 within the casting 26 is flat sided, being hexagonal in the present instance, and upon the hexagonal part is 90 mounted a ratchet wheel 31. A ratchet pawl 32 is mounted in the socket 28 and is normally moved by a spring 33 down into engagement with the ratchet wheel 31. A pin and slot connection 34 is provided in order 95 that the pawl may be arranged in either lifting or lowering position, i. e. may drive the ratchet wheel in either direction. 100

The sliding bearing 22 is threadedly engaged with a threaded portion 35 of the 105 shaft 15, the threads being so arranged that as the prime actuator is operated to progressively elevate the lifting member 13 the sliding bearing moves to the right (viewing Fig. 1). Finally it engages a collar 36 slid- 110

ably mounted in alignment with an opening 37 in the wall of the casting 26 adjacent the jack casing. This collar has a bevelled forward face 38 which is adapted to engage under a corner 39 of an operating tooth 41 of the pawl to lift and maintain this tooth out of engagement with the teeth 42 of the ratchet wheel 31 when the jack had lifted a predetermined amount. It will be manifest that 10 in thus lifting the pawl out of engagement and so maintaining it further manipulation of the manipulative device of the jack does not result in any further lifting or the application of any lifting force, the strokes of 15 the lever or handle being merely idle.

A spring split washer 43 is interposed between the ratchet wheel 31 and the end of the casting 26 and this spring normally pushes the ratchet wheel toward the left 20 (viewing Fig. 1) i. e. toward the collar 36. When the collar 36 is pushed over by pressure of the sliding bearing 22 the spring is compressed and the collar moved under the pawl.

25 In order that the parts may be assembled, the casting is cut away as indicated at 45 to permit the ratchet wheel, collar and spring to be inserted in place before the shaft 15 is positioned, positioning of the shaft and 30 securing of the plate 17 in position holding the parts assembled.

The opposite corner 46 of the tooth 41 is cut away so that when the finger piece 47 of the pawl is turned to permit lowering of 35 the jack, the ratchet tooth 41 will engage the ratchet wheel regardless of the position of the collar 36 and lowering may be accomplished.

It is thought that the invention and many 40 of its attendant advantages will be understood from the foregoing description, and it will be apparent that various changes may be made in the form, construction and arrangement of the parts without departing 45 from the spirit and scope of the invention or sacrificing all of its material advantages, the form hereinbefore described being merely a preferred embodiment thereof.

I claim:

50 1. In a jack the combination of elevating mechanism, a ratchet manipulating device for operating said elevating mechanism and comprising a ratchet wheel and a tooth movable into engagement therewith, and means having longitudinal movement with respect to the axis of said manipulative device proportionate to the rotation of said axis for causing engagement beneath the tooth when the elevating mechanism arrives at predetermined position to lift the tooth out of 55 position for engagement with the ratchet.

2. In a jack the combination of elevating mechanism a ratchet manipulating device for operating said mechanism, and means having a screw threaded advance proportionate to the elevation of the elevating mechanism and disengaging the tooth of the ratchet when the elevating mechanism arrives at predetermined position. 65

3. In a jack, the combination of a rotating prime actuator, a manipulating member embracing said prime actuator and having a tooth, a ratchet wheel mounted on said prime actuator, a bevel member embracing said prime actuator, means operable by and movable upon said prime actuator for thrusting said bevel member under the tooth of the ratchet for disconnecting said ratchet when the prime actuator has elevated the jack a predetermined amount. 70 75 80

4. In a jack, the combination of a rotating prime actuator, a manipulating member embracing said prime actuator and having a tooth, a ratchet wheel mounted on said prime actuator, a bevel member embracing said prime actuator, means operable by and movable upon said prime actuator for thrusting said bevel member under the tooth of the ratchet for disconnecting said ratchet when the prime actuator has elevated the jack a predetermined amount, said tooth being bevelled and reversible to permit lowering of the jack without engaging said bevelled member. 85 90 95

5. In a jack the combination of elevating mechanism, a ratchet manipulating device for operating the elevating mechanism and having a tooth for actuating said elevating mechanism to raise and lower a load, and means having longitudinal movement with respect to the axis of said manipulative device proportionate to the rotation of said axis for causing disengagement of the tooth when said elevating mechanism has lifted a load a predetermined distance, said tooth being movable in said disengaged position to a position for engagement with the ratchet to move it in the reverse direction. 100 105 110

6. In a jack the combination of elevating mechanism, a ratchet manipulating device for operating the elevating mechanism and having a tooth movable toward and from a ratchet wheel for actuating said elevating mechanism and means for lifting the tooth away from said ratchet wheel when the elevating mechanism has lifted a load a predetermined distance, said tooth being movable from its disengaged position into engagement with the ratchet wheel to move the ratchet wheel in a reverse direction. 115

JOHN B. HASTY.
